UNITED STATES PATENT OFFICE.

LENA PERLMAN, OF PHILADELPHIA, PENNSYLVANIA.

SURGICAL BAKER.

Application filed August 28, 1920. Serial No. 406,562.

To all whom it may concern:

Be it known that I, LENA PERLMAN, a citizen of the United States, residing at Philadelphia, county of Philadelphia, and 5 State of Pennsylvania, have invented a new and useful Improvement in Surgical Bakers, of which the following is a full, clear, and exact description, reference being had to the accompanying drawings, which form a 10 part of this specification.

This invention relates to an improvement in surgical bakers and is designed to provide a device of this character which is adapted for the treatment of different portions of the body.

The object of my invention is to provide a hollow, truss structure, of arch form, which is arranged to span the body, or the limbs of the patient, and in which the 20 lamps or treating elements are supported between the structural members, so that the treating elements are protected against injury, while the patient is protected from the danger of direct contact with the treating 25 elements.

A further object of my invention is to provide a light, rigid structure which will retain its shape when in use, so that the patient cannot be injured or burnt by the 30 collapse of the instrument, as well as an instrument which can readily be handled and which will not buckle or bend by handling.

The precise nature of my invention will 35 be best understood by reference to the accompanying drawings which will now be described, it being premised, however, that changes may be made in the details of construction, without departing from the spirit 40 and scope of my invention as defined in the appended claims.

Fig. 1 of the drawings is a perspective view of one form of my invention.

Fig. 2 is a face view thereof.

Fig. 3 is a sectional view on the line 45 3-3 of Fig. 2.

Fig. 4 is a similar view on the line 4-4 of Fig. 3.

In these drawings the reference character 50 10 designates truss forming members of arcuate form, there being one of such members at each end of the structure. These members are formed of light material and I have found that fibre is suitable for this 55 portion of the structure when the device is

properly braced. 11 and 11^a are longitudinal tie bars connected to the compression portions of the members 10, and 12 are similar members connecting the tension portions of these same members to each other. 60

These members 11 and 12 are formed of metallic strips of rectangular form, the ends of which are bent at right angles to form feet, and which are tapped to receive securing screws 13.

The two members 11^a are formed of strips of L-shape in cross section, and one of the flanges at each end is bent to form a foot, and which are also tapped to receive securing screws 13.

14 are the members having feet at their ends which are secured to the members 11^a and all the members 12.

The one end of each of these members 14, is connected to a member 11^a, and extend 75 in a radial direction to the one edge member 12. These members then extend over all of the members 12, and then extend in radial direction to the other member 11^a.

These members 14 are secured to the different members 12 by means of screws 15, the arrangement being such that the members 14 tie the members 12 to each other and thereby reinforce each other, while the members 14 are reinforced and retained in 85 their positions by the members 12. Mounted on the outside of the members 11 is a metallic reflector 16 which is secured in position by screws 17 which have a threaded engagement with the members 11. 18 are 90 also reflector plates on the inner sides of the truss members 10 and which are held in position by the screws 13 which secure the members 10 to the members 11, 11^a and 12.

Secured to the central member 11 by 95 means of screws 19, is a handle 20 by which the baker can be carried.

21 are sockets secured to the truss members 10 and are connected to each other and a switch member 22 by suitable wires, and 100 which sockets are arranged to receive electric light bulbs 23.

The various members are so placed that the lamp bulbs are guarded by the various structural elements, and the patient on 105 whom the instrument is used is protected from coming in contact with the bulbs.

The advantages of my invention result from the provision of a surgical baker of 110 arcuate form, built up of a plurality of

structural elements to form a rigid and light structure which encase the lamps or treating elements, whereby the lamps are protected, as well as the patient from contact 5 with the lamps.

Having now fully described my invention, what I claim and desire to protect by Letters Patent is:—

1. An arch-shaped surgical baker, having 10 arcuate shaped end members, an outer frame formed of structural elements connecting the outer edges of the end members to each other, an inner frame formed of a plurality of spaced structural elements connecting the 15 inner edges of the end members to each other at different points throughout the length of the end members, and lamps supported on one of said end members and extending between the frames, the inner 20 frame also forming a guard for lamps.

2. An arch-shaped surgical baker, having arcuate shaped end members, an outer frame formed of structural elements connecting the outer edges of the end members to each 25 other, a reflector secured to the outer frame, an inner frame formed of a plurality of spaced structural elements connecting the inner edges of the end members to each other at different points throughout the length of 30 the members, and lamps supported on one of said end members and extending between

the frames, the inner frame also forming a guard for lamps.

3. An arch shaped surgical baker, having arcuate shaped end members, a plurality of 35 spaced longitudinal members connected to the outer edges of the end members, an arc shaped reflector secured to the longitudinal members between the end members, a plurality of longitudinal members secured to 40 the inner edges of the end members forming an inner frame, a reflector on the inner face of each end member held in position by being secured between the ends of the longitudinal members and the end members, 45 a plurality of arcuate tie rods connected to the longitudinal members of the inner frame, the ends of said tie rods extending in radial directions and being secured to longitudinal members connected to the outer edges 50 of the end members, and treating elements supported on the end members between the arc-shaped reflector and the inner frame, the inner frame also forming a guard for the treating elements. 55

In testimony of which invention, I have hereunto set my hand, at Philadelphia, on this twelfth day of August, 1920.

LENA PERLMAN.
